LOCK

Max Troy, Brooklyn, N. Y.

Application November 5, 1935, Serial No. 48,410

4 Claims. (Cl. 292—39)

This invention relates to a lock which is designed and adapted to be used on the doors of the inner cylinder of a laundry washer.

The principal object of the invention is to incorporate means in connection with each door of an inner cylinder of a laundry washer in such manner that there will not be any projecting portions or sharp edges on the inside to tear or otherwise damage the articles being washed within the cylinder.

A further object of the invention is the provision of improved means of the indicated character which may be readily operated to tightly clamp or hold a door closed against its frame to avoid damage to the articles being washed, and also to be readily operated to release the door so that it may be opened to remove the washed articles.

A further object of the invention is the provision of means of the indicated character adapted to exert clamping pressure at a plurality of spaced points so as to tightly clamp a cross sectionally curved door against its frame for the purposes stated hereinabove.

With the foregoing and other objects in view the invention resides in the combinations, constructions and functions of the parts hereinafter fully described and illustrated in the accompanying drawings, in which—

Figure 1 is an outside view of an inner cylinder unit of a washer embodying the invention, and showing a door in closed position and its locking mechanism released.

Figure 2 is a view similar to Figure 1, but showing the locking mechanism locked to exert clamping pressure on the door.

Figure 3 is an enlarged section taken on the line 3—3 of Figure 1 and looking in the direction indicated by the arrows.

Figure 4 is an enlarged section taken on the line 4—4 of Figure 1 and looking in the direction indicated by the arrows.

Figure 5 is an enlarged section showing one of the latch members engaged and how it exerts clamping pressure to press the door against its frame.

Figure 6 is an enlarged section taken on the line 6—6 of Figure 2 showing another one of the latch members engaged for the purpose of exerting pressure to press the door against its frame.

Figure 7 is an enlarged view of the gear set and its crank spindle for operating the locking mechanism.

Figure 8 is a section taken on the line 8—8 of Figure 7 and looking in the direction indicated by the arrows.

In the illustrated embodiment of the invention there is shown a single unit of an inner cylinder of a washer used in laundries for washing various articles. This inner cylinder is made up of a

plurality of similar units which are bolted together end to end, and each of said units is subdivided into a plurality of sector-shaped compartments, each of which has a door and door opening for the introduction of the articles to be washed into the compartment and for their removal therefrom. The cylinder 10 is perforated in order to allow the washing solution to percolate through the articles being washed as the cylinder is being rotated. The cylinder unit has a plurality of inwardly projecting hollow ribs 11 which are also perforated. One rib 11 is adjacent one side of the door opening. A door frame surrounds the door opening which is rectangular. The door frame consists of a flange 12 on one of the radial walls of the cylinder, a strip 13 secured to a flange 14 of the rib 11, and rings 15. The flange 12 and the strip 13 are disposed at opposite ends of the door opening and the rings 15 are disposed, respectively, at opposite sides of said opening. The door opening is controlled by a door 16 which fits the frame surrounding the opening, said door being arcuate or circumferentially curved. The door has a plurality of hand holds 17 at one end thereof for sliding the door to opened and closed positions. A rabbeted strip 18 is secured to the flange 12 and serves as a stop to limit the sliding movement of the door 16 to its closed position. Parting rings or spacers 19 are secured, respectively, to the rings 15, and guide rings 20 surround the rings 19 and are secured thereto. The rings 15, 19 and 20 constitute guides for the door 16.

The door locking, releasing and clamping mechanism consists of the following parts. Four latch members 21 are mounted on the outside of the door 16. A pair of the latch members 21 is arranged near each end of the door. Each latch member 21 is held in place for axial movement by a bearing 22 secured to the door 16 on the outside. Each latch member 21 has a conical outer end 23. The latch members 21 are engageable, respectively, with keepers 24 secured to the rings 20. A pair of the keepers 24 are arranged at each end of the door opening so as to receive the outer ends 23 of the latch members 21, respectively, when the door 16 is in its closed position against the stop 18. Each keeper 24 has a conical hole therein slightly larger than the conical end 23 of the related latch member 21. Toggle means is employed to actuate the latch members 21 simultaneously. This toggle means consists of a turnable part or disc 26 on the outside of the door 16. Links 27 each have one end pivotally connected with the disc 26, as at 28, and its opposite end pivotally connected with one of the latch members 21 as at 29. Each link 27 has a turn-buckle 30 for increasing or decreasing the length of the link, in order to make necessary

adjustments to compensate for wear or other variations. The disc 26 has a radial arm 31. Linkage is provided consisting of members 32, 33 and 34, respectively. The member 32 has 5 one end pivotally connected with the arm 31 as at 35, and its other end is pivotally connected with one end of the member 33, as at 36. The other end of the member 33 has a bolt and slot connection 37 with one end of the member 34. 10 The member 33 has sliding movement in a guide 38 secured to the door. Turnable parts or discs 39 are mounted on studs 40, respectively, secured to the door 16. Each disc 39 has an arm 41, and there being a bolt and slot connection 42 between each arm 41 and the link member 34. 15 Each disc 39 has an arm 43 pivotally connected with one end of a link 44 as at 45, and the other end of said link 44 being pivotally connected with a latch member 21, as at 46. Each link 44 has a turn-buckle 47 to increase or decrease the 20 length thereof. A gear set or equivalent means is employed for turning the disc 26 to actuate the latch members 21 through the intervention of the linkage and the discs 39. The gear set 25 consists of a crank spindle 50 which is mounted transversely of the door 16 and has an outer non-circular end 51 to accommodate a suitable crank. A beveled gear 52 on the spindle 50 meshes with a beveled gear 53 on a worm 54 which meshes 30 with a worm gear 55 fast on a shaft 56. The shaft 56 extends transversely with respect to the door 16 and has an outer non-circular end 57 which is disposed in a similarly shaped hole in 35 the disc 26 to cause the latter to rotate in response to the rotation of the shaft 56. The disc 26 is held on the shaft 56 by a nut and washer 58 on the shaft 56. The gear set is enclosed in a casing or housing 59 secured to the inside of the door 16 as at 60. The shaft 56 of the gear 55 being directly connected to the disk 26 prevents 40 reverse rotation of the disk 26 because the gear 55 can not turn the worm 54; hence unintentional release of the latch members will be prevented. 45

If desired, as shown in the present instance, another latch member 61 of a somewhat different type from the latch members 21 may be employed. The latch member 61 is pivotally connected as at 62 with one end of a link member 63, whose other end is connected with the link member 34 by a bolt and slot connection 64. The link member 63 is guided by a guide bearing 65 secured to the door 16. A keeper block 66 is secured within the rib 11 in line with the latch member 61. The block 66 has an oblique notch 67 therein which receives the oblique bill 68 of the latch member 61. When the door 16 is in its closed position, it will be possible to move 50 the latch member 61 with respect to the keeper block 66, and the bill 68 will enter the notch 67 setting up a camming action and thus forcefully press the adjacent end of the door 16 tightly against the frame strip 13, by manipulating 55 the spindle 50, and through the intervention of the disc 26, arm 31, and link members 32, 33, 34 and 63. The other end of the door 16 will be forced under the strip 13 thereby tightly pressing said end against the frame. 60

From the foregoing it will be obvious that the door 16 may be readily slid into its opened and closed positions by means of the hand hold 17. When the door 16 is in its closed position it may 70

be effectively secured or locked by manually operating the spindle 50 by a suitable crank which will cause all of the latch members to be engaged with their keepers or disengaged therefrom. It will be obvious that by reason of the provision and arrangement of parts set forth the door 16 will be clamped tightly all around against its frame; that there are no sharp edges projecting inside of the cylinder compartment to damage any of the articles being washed; and that the locking and releasing of the door 16 may be conveniently done. 10

I claim:

1. A lock for a door including latch mechanism adapted to be used with keepers, comprising primary latch members slidably mounted on said door at opposite sides thereof engageable with and disengageable from said keepers respectively when said door is in its closed position, said primary latch members embodying camming means 15 cooperating with said keepers to exert pressure on the sides of the door when the primary latch members are engaged with the keepers in such manner that the sides of the door will be forced tightly closed, an auxiliary latch mechanism at one end of said door, a link mounted for movement on said door longitudinally thereof and having one end pivotally connected with said auxiliary latch member, means connected with said link and said primary latch members for causing the primary latch members and the auxiliary latch member to function simultaneously, said means causing said primary latch members to be forced outwardly into said keepers while pulling said auxiliary latch member into functioning position, and power means connected with the first mentioned means for actuating said first mentioned means, said power means including a worm gear set which prevents unintentional release of the various latch members. 25

2. In a locking mechanism of the character described, latch mechanism adapted to be used with keepers, comprising latch members for securing a closure in closed position, there being one of said keepers for each of said latch members, 45 and means connected with said latch members which is operable to move said latch members simultaneously into and out of engagement with their keepers, said means including a gear set which functions to prevent unintentional operation of said means and consequent release of the latch members. 50

3. In a locking mechanism of the character described, a latch mechanism adapted to be used with keepers, comprising latch members for securing a closure in closed position, there being one of said keepers for each of said latch members, a rotary part, means connecting the latch members with said part, and gearing including 55 a worm and gear for actuating said means. 60

4. In a locking mechanism of the character described, a latch mechanism adapted to be used with keepers, comprising a plurality of cam latch members mounted for movement with respect to said keepers respectively, and means connected with said latch members which is operable to move said latch members simultaneously into and out of engagement with their keepers, said means including a gear set which prevents unintentional release of the latch members. 70

MAX TROY.
